ROTARY ANODE X-RAY TUBE

Alexander H. Leighton, Minneapolis, Minn., assignor to Westinghouse Electric Corporation, East Pittsburgh, Pa., a corporation of Pennsylvania

Application October 27, 1948, Serial No. 56,706

4 Claims. (Cl. 250—148)

1

The present invention relates to X-ray tubes and more particularly to such tubes provided with a rotary anode.

Rotary anode X-ray tubes have long been known to the art and possess the advantage that the electron beam impinges upon substantially the entire surface of the tungsten target due to rotation of the anode which thus prolongs the life of the target and hence the entire tube. In addition, since the electron beam is concentrated only for a brief interval of time at one spot of the tungsten target during its rotation, a rotary anode X-ray tube can withstand a somewhat greater energy loading than a conventional stationary anode X-ray tube which thus results in a greater intensity of the generated X-rays.

Despite these advantages, however, one serious problem with rotary anode X-ray tubes has been the conduction of heat away from the tungsten target. This problem exists because of the fact that the heat has hereto had to be transmitted through the bearings, which constitute the only metallic connection between the rotating anode and other metallic parts of the tube, so that the generated heat is finally dissipated exteriorly of the tube to the atmosphere, or to a cooling and insulating material circulating through stationary parts of the anode.

It is accordingly the primary object of the present invention to provide an X-ray tube having a rotary anode wherein the heat radiating area of the anode is increased as well as the length of its thermal conducting path thus decreasing the temperature of the bearings for the anode during operation of the tube.

Another object of the present invention is the provision of an X-ray tube having a rotary anode formed of plates to increase the heat radiating surface of the anode so that a larger percentage of the heat generated during operation of the tube is dissipated by radiation from the anode thus decreasing the amount of heat dissipated through conduction to the bearings for the anode.

Still further objects of the present invention will become obvious to those skilled in the art by reference to the accompanying drawing wherein:

Figure 1 is a fragmentary view in cross section of a rotary anode X-ray tube constructed in accordance with the present invention.

Figure 2 is a sectional view taken on the line II—II of Figure 1.

Figure 3 is an elevational view of a modification which the rotary anode of the present invention may take, and

Figure 4 is a sectional view taken on the line IV—IV of Figure 3.

Referring now to the drawings in detail the X-ray tube as shown in Figure 1 comprises an evacuated vitreous envelope 5 provided with a re-entrant stem 6 to which the anode electrode is hermetically sealed. This is accomplished by

2

providing the anode with a metallic cylindrical member 7, the lower periphery 8 of which is sealed to the upper peripheral edge of the reentrant stem. To effect such seal the cylindrical member 7 is formed of a metal having substantially the same coefficient of expansion as the vitreous envelope material, such, for example, as an alloy of cobalt, nickel, and iron, and commercially known as "Kovar." Extending coaxially of the cylindrical member 7 is the anode conducting support 9, which may be formed of a good heat and electrical conducting material, such as copper, and having a flanged portion 10, the under surface of which is welded or similarly secured to the upper periphery of the cylindrical metallic member 7 to form an hermetic seal therewith. A rotor supporting shaft 12 threadedly engaged the conducting support 9 and may be held against unloosening by a set screw 13. A pair of ball bearings 14 are carried by this supporting shaft 12 and are held in spaced relation with respect to each other by a sleeve or the like 15.

The rotor proper of the rotary anode comprises a hollow shell 16 frictionally engaging the ball races 14 and held in such position by a threaded retaining ring 17, with the latter being locked in place by a set screw or the like 18. Although this shell 16 is formed of a good heat and electrically conducting material, such as copper or the like, its outer surface is provided with an annular ring or spaced laminations 19 of a magnetic material, such as iron, so as to cause rotation of the shell 16 about the ball races 14 under the influence of a magnetic field generated by the stator 20 which surrounds the vitreous envelope 5 of the rotary anode X-ray tube in the customary manner.

By reference to Figure 1, it will be noted that the shell 16 is provided with a tapered closed end 40 from which projects a metallic stud or the like 22 of good heat and electric conductivity. Riveted, welded, or otherwise secured to this stud is a metallic plate or preferably a disk 23 of substantial diameter and relatively small cross section, thus providing considerable heat radiating area from its surface, while at the same time allowing heat to be conducted to the shell by the stud 22. A second metallic disk 24 is in turn supported through a plurality of spacing rivets or the like 25, from the disk 23 and the refractory metal target 26, preferably of tungsten, is supported from the second disk 24 by a central stud 27 riveted or otherwise secured to both the target 26 and second disk 24. It will be noted that the central rivet 27 is of somewhat larger diameter than the rivets 25 supporting the disk 24, for the purpose of better heat conduction, so that the heat generated at the tungsten target 26 is conducted through the central rivet 27 to the disk 24 for dissipation through radiation therefrom due to its relatively large surface area.

Since the surface of the disk 24 itself is in-

sufficient to radiate all of the heat some will flow to the disk 23 both by radiation and conduction through the studs 25, so that the radiating surface of the disk 23 is thus added to that of the disk 24 for the rapid dissipation of the heat. Naturally some heat will also be conducted by the stud 22 to the shell 16 and, thence by the sleeve 15 and ball bearings to the rotor shaft 12 and anode conducting support 9, exteriorly of the tube 5 to the atmosphere. However, due to the area of the disks 23 and 24 the greater dissipation of the heat will be by radiation to the walls of the X-ray tube 5 and thence to the atmosphere, while the amount finally conducted through the ball bearings 14 will be confined to a relatively small amount.

In order to still further decrease the amount of heat finally conducted by the ball bearings 14 the number of disks employed may be increased as shown in the modification of Figure 3, where two additional disks 28 and 29 are employed thus doubling the radiating surface area over that illustrated in Figure 1. Of course the number of disks can be increased, being limited only by the spacing required between the tungsten target 26 and the thermionic cathode 30, and the length of the X-ray tube.

It thus becomes obvious to those skilled in the art that an X-ray tube of the rotary anode type is herein provided in which the heat radiating surface of the anode is so increased, as well as the thermal conductive path thereof, that the temperature to which the bearings is subjected during operation of the tube is decreased substantially to a minimum. Moreover, by providing the anode with a plurality of disks having a substantially large surface area compared with their cross section, the greater percentage of the heat generated at the anode target is dissipated by radiation through the tube walls, thus confining the heat dissipated by conduction through the metallic parts of the anode to a very small amount which prolongs the useful life of the X-ray tube yet allows a greater energy loading without deleterious effects ensuing.

Although two embodiments of the present invention have been shown and described, it is to be understood that still further modifications thereof may be made without departing from the spirit and scope of the appended claims.

I claim:

1. A rotary anode X-ray tube comprising an evacuated vitreous envelope provided with a metallic anode and a cathode therein, said anode having a target at which heat is generated during operation of said X-ray tube and including a rotatable member journaled for rotation about the longitudinal axis of said tube, and said anode comprising a series of annular spaced metallic disks completely spaced from each other to expose their entire respective plane surfaces and supported from each other by a connecting member independent of said rotatable member for increasing the heat dissipated by radiation from the anode surface and to decrease the anode heat dissipated by conduction to a minimum.

2. A rotary anode X-ray tube comprising an evacuated vitreous envelope provided with a metallic anode and a cathode therein, said anode having a target at which heat is generated during operation of said X-ray tube and including a rotatable member journaled for rotation about the longitudinal axis of said tube, and said anode comprising a series of superimposed annular disks of relatively large surface area angularly

disposed with respect to the axis of rotation of said anode and completely spaced from each other to expose their entire respective plane surfaces and supported from each other by uprights of small cross sectional area entirely independent of said rotatable member for increasing the anode heat dissipated by radiation from the anode surface and to decrease the anode heat dissipated by conduction through the metallic anode to a minimum.

3. A rotary anode X-ray tube comprising an evacuated vitreous envelope provided with a metallic anode and a cathode therein, said anode having a target at which heat is generated during operation of said X-ray tube and including a rotatable member journaled for rotation about the longitudinal axis of said tube, said rotatable member comprising a metallic shell frictionally engaging a pair of bearings and provided with a stud of smaller diameter than said shell and disposed coaxially of the axis of said tube, and said anode including a series of annular disks of relatively large surface areas completely spaced from each other to expose their entire respective plane surfaces with the first disk in the series being supported by said stud and the remainder of said disks being supported from each other independently of said stud, for increasing the anode heat dissipated by radiation from the anode surface and to decrease the anode heat dissipated by conduction through said metallic shell to the frictionally engaged bearings.

4. A rotary anode X-ray tube comprising an evacuated vitreous envelope provided with a metallic anode and a cathode therein, said anode having a target at which heat is generated during operation of said X-ray tube and including a rotatable member journaled for rotation about the longitudinal axis of said tube, said rotatable member comprising a metallic shell frictionally engaging a pair of bearings and provided with a stud of smaller diameter than said shell and disposed coaxially of the axis of said tube, and said anode including a series of annular disks of relatively large surface areas completely spaced from each other to expose their entire respective plane surfaces with the first disk in the series being supported by said stud and the remainder of said disks being supported from each other by radially disposed studs independent of the stud of said shell, for increasing the anode heat dissipated by radiation from the anode surface and to decrease the anode heat dissipated by conduction through said metallic shell to the frictionally engaged bearings, and said anode target being connected by a metallic stud of larger diameter than said radially disposed studs to the last of said disks in the series remote from said metallic shell.
